Primary Examiner — Dana K Weiland*Assistant Examiner* — Russell Carnell Smith, Jr.(74) *Attorney, Agent, or Firm* — ScienBiziP, P.C.(57) **CLAIM**

The ornamental design for a sound card controller, as shown and described.

DESCRIPTION

FIG. 1 is a front perspective view of a sound card controller, showing my design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of an area labeled 9 in FIG. 1. The evenly-spaced broken lines show portions of the sound card controller that form no part of the claimed design. The dot-dash broken lines containing portions of the sound card controller in FIG. 1 and illustrated in an enlarged view in FIG. 9 form no part of the claimed design.
